Original "Sure-Set" Golf Training Aid; Aug. 2012; 4 pgs.

Primary Examiner — Catherine A Tuttle

(74) Attorney, Agent, or Firm — Gardner Groff
Greenwald & Villanueva, PC(57) **CLAIM**

The ornamental design for a sports training aid, substantially as shown and described.

DESCRIPTION

FIG. 1 is a perspective view of the sports training device embodying our new design;

FIG. 2 is a top plan view thereof;

FIG. 3 is a bottom plan view thereof;

FIG. 4 is a front elevational view thereof; and,

FIG. 5 is a rear elevational view thereof.

Portions shown in broken lines are for illustrative purposes only and form no part of the claimed design.

1 Claim, 4 Drawing Sheets(56)
